UNITED STATES PATENT OFFICE.

GEORGE S. LEWIS, OF CHICOOPEE FALLS, MASSACHUSETTS, ASSIGNOR TO J. STEVENS ARMS & TOOL COMPANY, OF CHICOOPEE FALLS, MASSACHUSETTS, A CORPORATION OF MASSACHUSETTS.

MACHINE FOR SEALING ENVELOPS.

1,046,472.

Specification of Letters Patent.

Patented Dec. 10, 1912.

Application filed July 21, 1911. Serial No. 639,840.

To all whom it may concern:

Be it known that I, GEORGE S. LEWIS, a citizen of the United States, residing in Chicopee Falls, in the county of Hampden, 5 in the State of Massachusetts, have invented certain new and useful Improvements in Machines for Sealing Envelops, of which the following is a specification, reference being had to the accompanying drawings, 10 forming a part hereof.

This invention relates to machines for sealing envelops in which the flaps of the envelops as they are placed in the receptacle therefor, are turned forward by flap turning devices, the gummed surfaces are moistened, the envelops are then drawn out of the receptacles, flap foremost by feeding rolls, the flaps are then turned against the envelops, and the envelops are then passed 15 between pressing rolls by which the moistened flaps are pressed firmly against the bodies of the envelops.

The object of the invention is to improve the construction of such machines in various particulars; first, with respect to the feeding of the envelops, so that the envelop which is to be operated upon shall not be twisted out of position by the flap turning devices, and so that the envelops shall be fed from the receptacle properly without regard to variations in thickness; second, with respect to the devices for turning the moistened flap of each envelop against the body of the envelop, so that such operation shall be performed with certainty; third, with respect to the feeding rolls, so that notwithstanding their peculiar shape, the driving gears shall continue to mesh properly and, fourth, with respect to the feeding devices, so that the envelop shall not be carried around the rolls.

The invention will be more fully explained hereinafter with reference to the accompanying drawings in which it is illustrated and in which—

Figure 1 is a view showing in side elevation a machine which embodies the present improvements. Fig. 2 is a view of the same partly in longitudinal section and on a 50 larger scale, the receptacle for the unsealed envelops being partly broken off to save space. Fig. 3 is a detail view partly in section on the plane indicated by the line 3—3 of Fig. 2 looking in the direction of the 55 arrows. Fig. 4 is a detail view illustrating

particularly the application of the strippers to one of the pressing rolls. Figs. 5, 6, and 7 are detail views of the escapement device.

The machine shown in the drawing comprises a suitable bed plate *a* upon which are 60 mounted the frame *b* which supports the sealing devices and their operating means, and the receptacle *c* in which are placed the envelops to be sealed. In order that a large number of envelops may be placed in the receptacle at one time, without danger of clamping the lowermost envelop too firmly in the bottom of the receptacle by reason of the weight of the entire number, the receptacle *c* is formed with an inclined bottom *d* on which the envelops may be placed, 65 such inclined bottom terminating in an abrupt shoulder *d*¹ which forms a stop for the lowermost envelop which then lies flap downward, upon the bottom plate *d*², which is cut out as at *d*³ so as to permit the flap 70 turning device to engage the flap of the envelop and turn it forward. The shoulder *d*¹ against which the rear edge of the envelop rests, assists in preventing such twisting 75 of the envelop as might interfere with its proper progress through the machine.

In machines of the character to which this invention particularly relates the envelops rest flap downward and forward, or 80 to the right in Figs. 1 and 2, upon the plate *d*² which is cut away as at *d*³ to permit the 85 rotating finger *e* on a shaft *e*¹ of the machine to turn the flap forward into position to be first moistened and then grasped 90 so that the whole envelop is pulled forward by the flap from the receptacle *c*. In this movement of the flap it is turned to a substantially horizontal position or into a 95 position in the same plane with the body of the envelop and is grasped and pulled forward while in such plane. This positioning of the envelop is taken advantage of to control the feed of the envelops from the receptacle *c* so that only the one envelop shall 100 be permitted to escape from the receptacle at a time regardless of any variation in thickness of successive envelops with their contents. To enable this result to be accomplished there is mounted at the delivery 105 end *c*¹ of the receptacle a gravity escapement device *f* which is shown in detail in Figs. 5, 6 and 7. As shown it comprises an elongated horizontal lip *f* which is suitably supported so that it may be raised by the 110

flap of each envelop as the latter is turned up, shall rest on the body of that envelop as it is drawn out, and shall fall in front of the next envelop before its flap is turned. For this purpose the escapement f could be carried by a vertical bar f^1 , which is engaged by screws f^2 , which pass through slots f^3 in the wall c^1 of the receptacle. By this device the envelop next above that which is to be drawn out at the bottom of the receptacle is held back regardless of the thickness of either of the envelops, with their contents, while it is thus lifted by the turning of the flap to the height which is necessary to release the lowermost envelop, also regardless of the thickness of such envelop with the contents.

It is desirable in some cases to provide in the receptacle an internal inclined guide wall c^2 but the escapement device is preferably supported so that its movement shall be in a vertical plane.

The present machine, like the machine upon which it is an improvement, has skeleton feed rolls g and h , the lower feed roll g comprising a shaft g^1 , a hub g^2 , a central disk g^3 and lateral disks g^4 , all of the disks being cut away or recessed, as indicated at g^5 in Fig. 2, and the disks g^4 being provided with moisteners g^6 which coöperate with a moistening roll g^7 . The upper roll h , also comprises a shaft h^1 , a hub h^2 , a central disk h^3 and lateral disks h^4 , the several disks h^3 and h^4 coöperating with the corresponding disks g^3 and g^4 , being cut away or recessed, as at h^5 . The roll h is pressed down in its slotted bearings toward the roll g by spring actuated pressers h^6 and the two rolls are geared together by intermeshing gears indicated at h^7 . The disks g^3 and g^4 , for that portion of their circumference which is of the maximum diameter, coöperate with the corresponding portions of the disks h^3 and h^4 to grip the forwardly turned flap of the envelop and draw the envelop forward out of the receptacle c . The gears h^7 are therefore held firmly in mesh during that portion of the rotation of the rolls. In order to prevent the improper meshing and clattering of the gears which would otherwise take place when the pressure of the upper rolls is not supported by the disks g^3 and g^4 of the lower roll, the lower roll is provided with supplemental disks g^8 and the upper roll with supplemental disks h^8 by which the upper roll is properly supported when it is not supported by the mutilated disks g^3 and g^4 .

In the machine to which the present improvements are applied, as such machine has been constructed heretofore, the turning of the flap of each envelop downward from the plane of the body, was effected by a star wheel located in such position as to strike the flap of each envelop

as it protruded from the grasp of the feed rolls and turn it down. Such star wheel, however, is found not to operate satisfactorily under all conditions. In the present machine, therefore, the turning of the flap of the envelop downward from the plane of the body is accomplished by causing the flap to adhere slightly to the surface of the lower roll g or, more exactly, to the surface of the middle disk g^3 . This is accomplished by small spurs g^9 which are set into the disk g^3 , coöoperating with pads h^9 , preferably of rubber, carried by the disk h^3 . The spurs prick the flap of the envelop and cause it to cling slightly to the disk g^3 so that it is carried around by the disk until it meets the strippers i , which are suitably shaped rods mounted upon the frame of the machine and act to disengage the flap from the lower roll. When such disengagement takes place, however, the forward edge of the body of the envelop has been carried far enough forward so that the fold will enter with certainty between the first pair of presser rolls k , k^1 . To prevent the possibility of an envelop being carried around the lower presser rolls k^1 , k^3 , through slight sticking of the flap side of the envelop to the rolls, such rolls are preferably provided with strippers k^4 and k^5 , which are merely bent fingers k^6 carried by a rod k^7 , and rest in circumferential grooves k^8 of the lower rolls, as clearly shown in Fig. 4.

It will be understood that the several features of improvement shown and described herein are capable of use independently of each other and that the form and arrangement may be varied to suit different conditions of use. The invention, therefore, is not limited to the precise construction, arrangement and combination of parts shown and described herein.

I claim as my invention:

1. In a machine for sealing envelops, the combination with a receptacle for the envelops to be sealed having a discharge opening in its bottom, a vertically movable escapement device and means to turn the flap of an envelop forward toward a position in the plane of the envelop and to lift said escapement in this turning movement.

2. In a machine for sealing envelops, the combination of a receptacle for the envelops to be sealed having a discharge opening in its bottom, a vertically movable gravity escapement device and means to turn the flap of an envelop forward toward a position in the plane of the envelop and to lift said escapement in this turning movement.

3. In a machine for sealing envelops, the combination of a receptacle for envelops to be sealed, having a slotted bottom plate with a discharge opening at one end, a gravity escapement device mounted on the end of the receptacle to move in a vertical plane

transverse to the plane of the envelop, and means to turn the flap of an envelop forward toward a position in the plane of the envelop and to lift said escapement in this 5 turning movement.

4. In a machine for sealing envelopes, the combination of upper and lower feed rolls, one of said rolls having a spur to engage the flap of the envelop and cause it to cling 10 to the surface of the roll and be turned thereby out of the plane of the body.

5. In a machine for sealing envelopes, the combination of upper and lower feed rolls, one of said rolls having a spur to engage 15 the flap of the envelop and the other of said rolls having a coöperating pad.

6. In a machine for sealing envelopes, the combination of a receptacle for the envelopes to be sealed, a flap turning device to turn 20 forward the flap of each envelop in succession, and recessed feed rolls to engage the flap and feed the envelop forward, one of said rolls having a spur to engage the flap of the envelop.

25 7. In a machine for sealing envelopes, the combination of upper and lower feed rolls, a moistening device and presser rolls, one of said feed rolls being provided with means

to engage the flap of the envelop and cause it to cling to the surface of the roll and thereby to turn it out of the plane of the body 30 of the envelop, whereby the fold of the envelop is properly presented to the presser rolls.

8. In a machine for sealing envelopes, the 35 combination of feed rolls, a moistening device and presser rolls, one of said rolls having a spur to engage the flap of the envelop and cause it to cling to the surface of the roll and thereby turn it out of the plane of 40 the body of the envelop.

9. In a machine for sealing envelopes, the combination of feed rolls, a moistening device, presser rolls, means to cause the flap of the envelop to adhere to the surface of 45 one of the feed rolls and to be turned thereby out of the plane of the body of the envelop, and a stripper to disengage the flap from said feed roll.

This specification signed and witnessed 50 this 17th day of July 1911.

GEORGE S. LEWIS.
